UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

BREECH MECHANISM OF ORDNANCE.

1,080,268.

Specification of Letters Patent. Patented Dec. 2, 1913.

Application filed May 13, 1913. Serial No. 767,265.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Breech Mechanism of Ordnance, 10 of which the following is a specification.

This invention relates to breech mechanism of the kind in which the breech block is composed of two portions of which the rear or wedge portion is adapted, during the 15 unlocking of the mechanism, to slide on the rear face of the forward portion whereupon both portions are swung outwardly to uncover the breech opening.

According to this invention we so construct and arrange the parts of breech mechanism of the above stated kind that the said mechanism can be employed with guns using ammunition in which the projectile is separate from the powder charge as distinct 25 from those using fixed ammunition, for which purpose the front portion of the breech block is provided with an obturator (preferably of the de Bange type) mounted upon an axial vent and the rear portion is 30 furnished with suitable firing mechanism. This firing mechanism is carried by a lock frame which is so arranged in relation to the rear portion of the breech block that relative movement within certain limits can 35 take place between them during the initial unlocking and the final locking action of the breech mechanism. This relative movement is utilized to retract the firing needle and to permit it to move into contact with 40 the head of the primer.

In order that our said invention may be clearly understood and readily carried into effect the same will be described more fully with reference to the accompanying drawings in which:—

Figures 1 and 2 are longitudinal sections of the breech end of a gun provided with breech mechanism constructed in accordance with our invention, Fig. 1 showing the lock frame in section with the mechanism in the locked condition, and Fig. 2 showing the lock frame in elevation with the mechanism in the open condition. Fig. 3 is a rear view, of which the left half is a section taken approximately on the line 1—1 of Fig. 1, and

the right half is a rear elevation of Fig. 2. Fig. 4 is a section taken approximately on the line 2—2 of Fig. 1 (with the firing needle removed), and Fig. 5 is an enlarged view of a part of Fig. 1.

A is the breech end of the gun.

B is the rear or wedge portion and B' the front portion of the breech block.

B² is the obturator and B^{2x} the axial vent.

C is the lock frame.

In the example shown the axial vent passes through the front portion B' of the block and at its rear end is screw threaded to engage with a nut b' which serves the double purpose of a box slide and of the usual retaining nut for the axial vent. The rear portion of the nut b' is adapted to receive the lock frame C which during the locking and unlocking movements of the mechanism is guided on a downwardly projecting part b² of the nut. This lock frame has an extension c disposed in a recess b in the rear portion B of the block in such manner that a small amount of relative movement can take place between the extension c and the block during the initial unlocking and the final locking movements of the mechanism (see Figs. 1 and 5). This relative movement is as aforesaid utilized during the unlocking of the mechanism to retract the firing needle D from the head of the primer, and during the locking of the mechanism is utilized to permit the said needle to return to its firing position. For this purpose the lock frame C is under the control of a spring C' which tends to maintain the extension c in contact with the wall b^{2x} of the recess b, as shown in Fig. 2. The lock frame carries a retracting device preferably in the form of a bell crank lever D' as shown, one arm of which (viz. d) is adapted to engage with a collar on the needle D and the other arm (viz; d') with the aforesaid wall b^{2x} of the rear portion B of the breech block. The arm d is formed with a projection d^x adapted to engage in a recess in the nut b' as shown in Figs. 1 and 5.

When the mechanism is in the locked position (Figs. 1 and 5), the lock frame C is held against a stop and is thereby retained in contact with the lower wall of the aforesaid recess b as shown in Figs. 1 and 5. At the same time the bell crank lever D' is held in the position shown by the spring of the fir-

ing needle D, with the arm d' in contact with the upper wall b^x of the recess and the projection d^x in engagement with its recess in the nut b' . When the breech mechanism 5 is commencing its unlocking movement, the rear portion B of the block starts to slide on the front portion B' but the lock frame C, by the engagement of the projection d^x on the bell crank lever D' with the recess in the 10 nut b' , remains stationary. The bell crank lever is thereby rocked about its pivot (by the engagement of the wall d^x with the arm d') to disengage its projection d^x from the nut and retract the 15 needle D. The said needle is held in this position during the continued sliding movement of the rear portion B of the breech block by the engagement of the projection d^x with the surface of the extension b^2 of the 20 nut b' . When the final locking movement takes place the operations are reversed until, when the mechanism has nearly reached its fully locked position, the lock frame C is moved downward relatively to the rear portion B of the breech block by the engagement 25 of the said frame with the aforesaid stop. The projection d^x of the bell crank lever D' is then opposite its recess in the nut b' and the bell crank lever D' can be dis- 30 placed by the spring of the needle D to enable the latter to come into contact with the head of the primer. During the unlocking of the mechanism cam surfaces on the lock frame C coöperate with a toe piece E^x of an 35 extractor E and cause the latter first to extract and then rapidly eject the used primer as has been previously proposed by us. A spring controlled primer retaining catch E' is provided as is well understood. The 40 mechanism is shown as being actuated in the usual way by the engagement of a cam slot F in an arm F' on the axis pin F^2 , with a pin B^x on the rear portion B of the block. The firing mechanism may be either elec- 45 trical or percussive, or may be a combination of both. In the example shown, the firing mechanism is electrical, and the rear portion B of the breech block is provided with two spring controlled contacts d^2 , d^3 (Fig. 3) 50 in electrical connection with each other, one (viz; d^2) bearing against a nut on the firing needle D and the other (viz; d^3) against a fixed contact d^4 on the gun.

What we claim and desire to secure by Letters Patent of the United States is:—

55

1. In breech mechanism for ordnance, the combination with a breech block composed of two parts, the rear or wedge part being capable during the locking and unlocking of the mechanism of sliding on the rear face 60 of the forward part, of an obturator carried by said front part, a lock frame carried by the rear part, firing mechanism mounted in said lock frame, and means for causing relative movement to take place between 65 said rear part and the lock frame during the initial unlocking and the final locking action of the breech mechanism.

2. In breech mechanism for ordnance, the combination with a breech block composed 70 of two parts, the rear or wedge part being capable during the locking and unlocking of the mechanism of sliding on the rear face of the forward part, of an obturator carried by said front part, a lock frame loosely 75 carried by the rear part, firing mechanism mounted in said lock frame, and means for causing relative movement to take place between said rear part and the lock frame during the initial unlocking and the final lock- 80 ing action of the breech mechanism.

3. In breech mechanism for ordnance, the combination with a breech block composed of two parts, the rear or wedge part being capable during the locking and unlocking 85 of the mechanism of sliding on the rear face of the forward part, of an obturator carried by said front part, a lock frame loosely carried by the rear part, firing mechanism mounted in said lock frame, means for caus- 90 ing relative movement to take place between said rear part and the lock frame during the initial unlocking and the final locking action of the breech mechanism, a firing needle forming part of said firing mechanism, and means whereby said relative movement ef- 95 fects the retraction of the firing needle and permits it to move into contact with the head of the primer.

In testimony whereof we affix our signatures in the presence of two witnesses.

ARTHUR TREVOR DAWSON.
GEORGE THOMAS BUCKHAM.
